ORNAMENT AND MOUNTING THEREFOR

Oscar Frank Placeo, Providence, R. I., assignor
to Cohn & Rosenberger, Inc., New York, N. Y.,
a corporation of New York

Application November 9, 1935, Serial No. 49,059

8 Claims. (Cl. 63—20)

My present invention relates to the jewelry art, and has particular reference to jewelry ornaments suitable for use in brooches and other articles of jewelry.

5 Ornaments as heretofore used for pins, brooches, pendants and similar articles have been permanently mounted on a base which has attaching means such as pins, clamps, and the like, whereby it has not hitherto been feasible to use 10 the same ornament for different jewelry articles.

It is a principal object of my invention to devise a construction whereby the same jewelry ornament may be used for different ornamental purposes, the jewelry ornament being so constructed as to be releasably securable to a plurality of different mountings.

20 With the above and other objects and advantageous features in view, my invention consists of a novel arrangement of parts more fully disclosed in the detailed description following, in conjunction with accompanying drawing, and more specifically defined in the claims appended thereto.

In the drawing,

25 Fig. 1 is a plan view of a jewelry ornament embodying the novel invention;

Fig. 2 is a rear view thereof;

Fig. 3 is a rear view of the ornament element, removed from its base;

30 Fig. 4 is a front view of one form of ornament base;

Fig. 5 is a detail perspective, partly broken away, of a portion of the ornament base of Fig. 4;

Fig. 6 is a detail perspective, partly broken away, showing the corresponding portion of the ornament;

Fig. 7 is a rear view of the same ornament mounted on a different base;

Fig. 8 is a side view thereof, the clamp being 40 shown in dotted lines to indicate opened position; and

Fig. 9 is a rear view of a further modified form of base.

It has been found desirable to provide an ornament which may be releasably mounted on a plurality of different bases, whereby the same ornament may be used as for a brooch, a clip, a belt buckle, or other jewelry ornaments, thus permitting a great variety of uses for a single 45 ornament. To this end, I have provided the ornament with a plurality of interchangeable bases to which the ornament may be detachably secured, whereby the user possesses many different jewelry items, all however using the same 50 ornament.

Thus, referring to the drawing, I have provided an ornament 10 with a plurality of spaced lock elements 11 mounted on the rear thereof, see Fig. 3, as by welding, swaging, or the like. The preferred construction of the lock elements 5 is shown in Fig. 6 and includes a spherical head 12 having a reduced shank 13. Associated with the ornaments is a base 14, see Fig. 2, which may have a pin element 15 secured to the back thereof, with a hinge connection 16 and a catch 10 connection 17, both of standard type, the base 14 having a plurality of spaced catch sections 18, preferably consisting of openings 19, see Fig. 5, and side slots 20, wherein the lock elements 11 may be snapingly received for releasable 15 detention, the ornament 10 being thus detachably locked to the base 14 for use as a brooch.

Instead of using the base 14, which is equipped with a pin 15, a clip base 21 may be used, see Fig. 7, equipped with a spring pressed clip clamp 22, this base having a plurality of catch sections 23 similar to the lock sections 18. The clamp 22, see Fig. 8 has the usual lock teeth 24 and spring element 25, and is hingedly mounted in standards 26, whereby mounting the ornament 10 on the clip base 21 provides a jewelry clip 25 which uses the same ornament as was previously used with the pin base 14.

Other forms of bases may be provided to utilize the same ornament 10, in conjunction with 30 other jewelry bases. For example, a buckle base 27 may be provided, see Fig. 9, the base having a plurality of tabs 28 hingedly mounted in pivot ears 29, the tabs having the usual cam or toothed lower edges for gripping the ends of a strap or 35 belt. The base 27 is also provided with a plurality of catch sections 30, identical with the catch sections 18 whereby the same ornament 10 may be releasably snapped into engagement to the base 27, to thus function as part of a belt buckle. 40 Bases may also be provided for other jewelry uses, as for example shoe buckles, pendants, and the like to which the same ornament 10 may be releasably secured as desired, whereby the purchaser of a single beautiful ornament may 45 utilize this same ornament for performing a variety of jewelry functions.

While I have described a specific constructional embodiment of my invention utilizing a plurality of different bases, it is obvious that changes in 50 the type and number of locking elements used, in the shape and material of the ornament and of the bases cooperating therewith, and in the manner of assembling the parts, may be made to suit different jewelry requirements, without 55

departing from the spirit and the scope of the invention as defined in the appended claims.

I claim:

1. In combination, an ornament having a plurality of spaced lock elements mounted adjacent the periphery thereof, and a base having a central opening having a plurality of spaced catch elements positioned adjacent the periphery thereof comprising openings having resilient edges for receiving the lock elements, said base having means for detachably securing to a garment.
2. In combination, an ornament having a plurality of spaced lock elements mounted on the rear surface adjacent the periphery thereof, and a base having a central opening having a plurality of spaced catch elements positioned adjacent the periphery thereof comprising openings having resilient edges for receiving the lock elements, said base having means for detachably securing to a garment.
3. In combination, an ornament having a plurality of spaced lock elements mounted adjacent the periphery thereof, said lock elements comprising enlarged heads and relatively narrow shanks, and a base having a central opening having a plurality of spaced catch elements positioned adjacent the periphery thereof for receiving the lock elements, said catch elements comprising openings having resilient edges, said base having means for detachably securing to a garment.
4. In combination, an ornament having a plurality of spaced lock elements mounted adjacent the periphery thereof, said lock elements comprising enlarged heads and relatively narrow shanks, and a base having a central opening having a plurality of spaced catch elements positioned

adjacent the periphery thereof for receiving the lock elements, said catch elements comprising slotted openings having resilient edges, said base having means for detachably securing to a garment.

5. In combination, an ornament having a plurality of spaced lock elements mounted on the rear surface adjacent the periphery thereof, said lock elements comprising enlarged heads and relatively narrow shanks, and a base having a central opening having a plurality of spaced catch elements positioned adjacent the periphery thereof for receiving the lock elements, said catch elements comprising openings having resilient edges, said base having means for detachably securing to a garment.

6. In combination, an ornament having a plurality of spaced lock elements mounted on the rear surface adjacent the periphery thereof, said lock elements comprising enlarged heads and relatively narrow shanks, and a base having a central opening having a plurality of spaced catch elements positioned adjacent the periphery thereof for receiving the lock elements, said catch elements comprising slotted openings having resilient edges.

7. A jewelry ornament base comprising a sheet metal ring, having a plurality of spaced openings with resilient edges and having means for detachable securing to a garment.

8. A jewelry ornament base comprising a sheet metal ring, having a plurality of spaced slotted openings with resilient edges and having means for detachable securing to a garment.

OSCAR FRANK PLACCO.
